UNITED STATES PATENT OFFICE.

OLE A. INGEBRIGTSEN, OF KANSAS CITY, MISSOURI.

ARTIFICIAL LEG.

1,182,566.

Specification of Letters Patent.

Patented May 9, 1916.

Application filed March 16, 1915. Serial No. 14,668.

To all whom it may concern:

Be it known that I, OLE A. INGEBRIGTSEN, a subject of the Kingdom of Norway, residing at Kansas City, in the county of Jackson and State of Missouri, have invented a certain new and useful Improvement in Artificial Legs, of which the following is a specification.

My invention relates to improvements in artificial legs.

It relates particularly to artificial legs comprising upper and lower leg members pivoted to each other and the knee joint.

The object of my invention is to provide a simple, durable and efficient construction, by means of which a quick and positive forward swinging movement, while walking, may be imparted to the shin piece or lower leg member.

20 The novel features of my invention are hereinafter fully described and claimed.

In the accompanying drawings which illustrate the preferred embodiment of my invention, Figure 1 is a perspective view, partly broken away, of my improved artificial leg, and the suspending means with which it is provided. Fig. 2 is an enlarged central vertical section view of portions of the upper and lower leg members and some 25 of the parts connected therewith. Fig. 3 is a perspective view of the knee stop and links which are pivoted thereto.

Similar reference characters designate similar parts in the different views.

35 1 designates the upper leg member which is hollow and which is pivoted by a horizontal transverse tubular bolt 2 to the upper end of the lower leg member or shin piece 3, which is preferably hollow and which has 40 secured within it a knee stop 4 which extends upwardly through a rear opening 5 into the upper leg member 1, see Fig. 2. The knee stop 4 is provided with a transverse hole 6, through which extends the 45 pivot bolt 2.

The knee stop 4, forward of the pivot bolt 6, is provided with a forward extension 7, preferably bifurcated at its forward end and having pivoted to said bifurcated 50 forward end by a transverse bolt or pin 8, the lower ends of two links 9, which extend upwardly and diverge laterally from each other.

Suspending means are provided comprising, preferably, the usual suspenders 10 adapted to be supported by the shoulders of

the wearer. The suspenders 10 are provided with two front straps 11, which respectively extend through two loops 12, which are secured to the forward side of the 60 upper leg member 1, Fig. 1, and which are respectively secured to two rings 13.

A cord or strap 14, preferably of buckskin, has its forward ends respectively secured to the rings 13 and has a running connection with a vertical back strap 15, which is secured to the rear portion of the suspenders 10.

Two supporting members comprising 70 preferably, two straps 16 are respectively secured to the rings 13 and respectively extend through two openings 17 provided respectively in opposite sides of the upper leg member 1.

The lower ends of the supporting members 16 are respectively provided with slots 18, which are adapted to releasably engage two buttons 19 which are secured respectively to the upper ends of the links 9.

The knee stop 4 is preferably secured to 80 the inner rear wall of the lower leg member 3 and is preferably provided with a forward extension 20, which at its forward end is secured to the inner front wall of the lower leg member 3.

85 In the operation of my invention, as the person wearing the leg, raises the upper member 1 in walking forwardly, the suspenders 10, through the intermediacy of the supporting members 16, links 9, and knee stop 4, causes the lower leg member 3 to be swung positively forwardly, due to the upward pulling of the supporting members 16 and links 9, thereby drawing upwardly 90 the extension 7 of the knee stop, and thus 95 swinging the lower leg member 3 forwardly on the pivot bolt 2.

As the supporting members 16 are extended upwardly through the interior of the upper leg member 1, there is no binding 100 action on the knee, such as occurs in structures in which the suspenders are attached to the lower leg member at the forward side thereof.

I do not limit my invention to the structure shown and described, as modifications, within the scope of the appended claims, may be made without departing from the spirit of my invention.

105 What I claim is:—

1. In an artificial leg, an upper leg member, a lower leg member pivoted thereto, a

knee stop secured to the lower leg member, suspending means adapted to be supported by the body of the wearer, and a link having a non-running connection with said suspending means and pivoted to said knee stop forward of the pivotal connection between the two leg members.

2. In an artificial leg, a hollow upper leg member, a lower leg member pivoted thereto, a knee stop secured to the lower leg member, suspending means, and means supported by said suspending means and extending into the upper leg member and having a non-running connection with the knee stop forward of the pivotal connection between said leg members.

3. In an artificial leg, a hollow upper leg member, a lower leg member pivoted thereto, a member secured to the lower leg member, suspending means, and means supported by said suspending means and extending into the upper leg member and having a non-running connection with the third named member at a point forward of the pivotal connection between said leg members.

4. In an artificial leg, a hollow upper leg member, a lower leg member pivoted thereto, a third member secured to the lower leg member, a rigid link pivoted to said third member forward of the pivotal connection between the leg members, and suspending means extending into the upper leg member and having a non-running connection with said link.

5. In an artificial leg, a hollow upper leg member, a lower leg member, a knee stop secured to the lower leg member and extending into the upper leg member, a pivot

bolt connecting said two leg members and 40 extending through said knee stop, a link pivoted to said knee stop forward of said pivot bolt, and suspending means attached to said link.

6. In an artificial leg, a hollow upper leg 45 member, a lower hollow leg member pivoted thereto, a knee stop secured to and within the lower leg member at the rear inner side thereof and provided with a forward extension secured to the inner front of the lower 50 leg member, the knee stop extending upwardly into the upper leg member, a bolt mounted in the upper leg member, the knee stop being pivoted on said bolt and extending forwardly therefrom in the upper leg 55 member, and suspending means connected to the knee stop forward of said bolt.

7. In an artificial leg, an upper leg member, a lower leg member pivoted thereto, a 60 knee stop secured to the lower leg member, a bolt mounted in the upper leg member, the knee stop extending into the upper leg member and pivoted to said bolt, suspending means adapted to be supported by the body of the wearer and having two supporting members, and two rigid links pivoted at their lower ends to the knee stop forward of said bolt and diverging from each other at their upper ends, the upper ends of said 65 links being respectively secured to said two supporting members.

In testimony whereof I have signed my name to this specification in presence of two subscribing witnesses.

OLE A. INGEBRIGTSEN.
